Primary Examiner — Mark A Goodwin(57) **CLAIM**

The ornamental design for an operator station for a work machine, as shown and described.

DESCRIPTION

FIG. 1 is a top, front, left perspective view of an operator station for a work machine embodying our new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; and, FIG. 7 is a bottom plan view thereof.

The broken line representations in the figures show unclaimed environment or boundaries, and thus form no part of the claimed design.

1 Claim, 7 Drawing Sheets(56)
